(57) **CLAIM**

The ornamental design for a log splitter, as shown and described.

DESCRIPTION

FIG. 1 is a perspective view of one side and the front of the log splitter according to an embodiment of my new design; FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The dashed lines shown in the drawings represent portions of the log splitter and form no part of the claimed design.
